UNITED STATES PATENT OFFICE

FRED R. LONG, OF CATAWISSA, PENNSYLVANIA

SHOE EASING DEVICE

Application filed December 30, 1931. Serial No. 583,975.

This invention relates to an apparatus or device for manipulating or operating on shoes to stretch them or otherwise render them more adaptable to the foot of the wearer.

5 To that end the invention contemplates a simple, practical and reliable construction which permits of readily supporting the shoe while the various parts thereof are subjected to stretching or manipulating pressure. In 10 that connection, one of the features of the invention resides in the provision of a device including a plurality of adjustable instrumentalities whereby shoes of all sizes and styles may be subjected to the desired stretching pressure at more or less localized points according to the demands of the particular fitting.

A further object of the invention is to provide a device which not only permits the operator to stretch the shoes lengthwise and sidewise but also to flex or soften the heel or counter thereof, and raise the vamp.

With the above and other objects in view, which will become more fully apparent as the 25 nature of the invention is better understood, the same consists in the novel features of construction, combination and arrangement of parts as will be hereinafter more fully described, illustrated in the accompanying drawings and defined in the appended claims.

A preferred and practical embodiment of the invention is shown in the accompanying drawings, in which:

Figure 1 is a side elevation of the improved 35 device.

Figure 2 is a top plan view thereof.

Figure 3 is a front elevation.

Figure 4 is a detail view illustrating the 40 manner of mounting one of the detachable last members.

Figure 4a is a detail rear view of the vamp raising device.

Figure 5 is a detail plan view of the counter flexing means.

45 Similar reference characters designate corresponding parts throughout the several figures of the drawings.

Referring to the drawings, the device includes in its organization a body designated 50 generally as 1 having an attaching bracket

portion 2 whereby the body may be fixed to a bench, table or the like support.

The front end of the body is provided with the cross-head 3 (Fig. 2), the same being provided with a dove-tailed guideway 4. 55 This guideway receives a pair of oppositely spaced nut members 5 and 6 having the dovetail portions 5a and 6a slidable in said guideway. The said members 5 and 6 are suitably threaded to receive the oppositely threaded portions 7 and 8 of the single screw S having hand wheels 9 and 10 at each end thereof.

As will be observed from Figs. 1 and 2, angular last supports 11 and 12 are mounted on the members 5 and 6 and it will be clear 65 that by manipulating either the hand wheel 9 or the hand wheel 10 the said last supports may be moved toward and from each other. The said last supports 11 and 12 are adapted to receive the detachable toe last members A 70 and A', or, alternatively, the vamp raising last member B (Fig. 4).

For the purpose of facilitating the placing of the last members on the horizontal legs of the last supports 11 and 12, each of the 75 last members are provided with a socket portion 13 and a friction ball clutch device 14, from which, it will be apparent, that the last members may be easily and quickly fitted to the supports and likewise removed.

Beneath the body 1, and between the vertical legs of the last supports 11 and 12 there is provided a longitudinally disposed adjusting screw shaft 15. This shaft, supported as at 16 and 17 and carrying at its outer end a hand wheel 18, is intended to operate a heel piece 19. This heel piece is provided with guide portions 20 for engaging with the ribs or guide rails 21 on the bottom edge of the body 1, and, upon manipulation of the screw 80 15 through the hand wheel 18, may be shifted forward and backward as desired.

The upper part of the body 1 is provided with a stationary counter flexing anvil 22 which is adapted to receive the back of a shoe (Fig. 5) placed thereagainst in an inverted position so that the counter portion of the shoe may be operated upon by the movable counter flexing member 23. This member is provided with the guide portions 24 adapted 95 100

- to slide on the guide rails or ribs 25 on the upper edge of the support 1. The front face of the counter flexing member 23 is curved as indicated at 26 while the rear face is provided 5 with a wear plate 27 adapted to be engaged by a cam plate 28 pivotally mounted as at 29 on the post carried by the body and operated by the handle 30. It will be clear that the counter flexing member 23 may be moved 10 toward and from the member 22, thereby to soften or manipulate the counter of the shoe placed between said members which serve as jaws to grip the counter of the shoe therebetween.
- 15 In connection with the vamp-raising device B shown in Fig. 4a, it will be understood that the same is made in one piece and is provided with an inclined vamp engaging front face B' for engaging the vamp of the shoe 20 while its rear face is provided with a socket B² of sufficient width to receive the two last supports 11 and 12. After the vamp raising device is mounted on the ends of the supports the hand wheels 9 or 10 may be operated to 25 force the outer edge of the members 11 and 12 in frictional engagement with the edges of the slot. This provides an easy and quick way of attaching and removing the vamp-raising last.
- 30 The attaching portion 2 may also be provided with a hinge so that instead of connecting the part 2 directly with the support, the hinge may be connected thereto and thus permit of the entire device being swung upwardly to a vertical position to be out of the way. The hinged knuckle 31 is integral with the part 2 while the leaf 32 is connected with the knuckle by means of a pin 33. It will, of course, be understood that in the event the 35 part 2 is secured to the support by screws or other fastenings it will not be necessary to fasten the hinge. On the other hand, if the hinge is used, it is not necessary to fasten the body directly to the support.
- 40 Without further description it is thought that the features and advantages of the invention will be readily apparent to those skilled in the art, and it will of course be understood that changes in the form, proportion and minor details of construction may 45 be resorted to, without departing from the spirit of the invention and scope of the appended claims.
- I claim:
- 55 1. A shoe easing device including a body having means at one end for attaching the same to the support, a cross-head at the end of the body opposite the point of support, a pair of oppositely adjustable last supports 50 slidably mounted in said cross head, a heel piece slidably carried by the body at the underside thereof, and means for adjusting the heel piece toward and away from said last supports.
- 60 65 2. A shoe easing device including a body having means at one end for securing the same to a support, a cross-head at the opposite end of the body and having a guideway, last means adjustable in opposite directions in said guideway, a heel piece having a slidable 70 guiding engagement with the underside of the body and a screw shaft mounted longitudinally of the body and connected with the heel piece whereby manipulation of the screw shaft will adjust the heel piece with reference 75 to the last means.
3. A shoe easing device comprising a body having attaching means at one end and a cross head portion at the other end, said latter portion being provided with a guideway, a 80 pair of oppositely adjustable nut members including portions engaging in said guideway, a single screw shaft having threaded portions of opposite pitch operatively engaging said nut members whereby manipulation of 85 said screw shaft will move said nut members, last members carried by said last supports, a heel piece arranged beneath the body, and a screw journaled in the body longitudinally thereof and having a portion extending between the last supports, and a manipulating wheel on the end of said screw shaft located between the said last supports.
4. A shoe easing device including a body having means at one end for attaching the 90 same to a support, a cross head at the end of the body opposite the attaching portion, said cross head having a guideway, nut members slidably mounted in said guideway, angular last supports mounted on said nut members, 95 a single screw shaft having threaded portions of same pitch but opposite hand respectively engaging with said nut members, hand wheels at opposite ends of the shaft whereby the latter may be turned to move the last 100 members toward and from each other, last members carried by the angular last supports, a heel piece mounted beneath the body, a screw shaft journaled longitudinally of the body and beneath the same, said screw shaft 105 being operatively connected with the heel piece and the forward end thereof projecting between the last supports and a hand wheel carried by the end of the shaft which projects between the last supports.
5. A shoe easing device including a body, nut members adjustably mounted in the body, last supports depending from said nut members and having horizontal offset portions, means for adjusting said nut members toward 110 and from each other, and last members provided with sockets having friction clutch means therein for receiving and engaging the horizontal portions of the last support.
6. A shoe easing device including a body 115 adapted to be mounted on a support, last units carried by the body, means for maintaining and adjusting the said units transversely of the body in parallel relation, and a heel piece arranged beneath the body and 120
- 65 70 75 80 85 90 95 100 105 110 115 120 125 130

adjustable longitudinally thereof thereby to move toward and away from said last units.

7. A shoe easing device including a body having attaching means, a pair of last supports carried by the body, means for slidably mounting said supports to move transversely of the body and to maintain them in parallel relation, and an adjustable heel piece mounted beneath the body and adapted to move at right angles to the path of adjustment of the last supports.

8. A shoe easing device including in combination, a body, an adjustable heel piece carried by the body, last supports carried by the body, means for adjusting said last supports toward and from each other and maintaining the same in parallel relation, and a vamp raising member adapted to be fitted to the last supports and held thereon by separation of said supports, said vamp raising member having an inclined vamp engaging face.

9. A shoe easing device including a body having an offset bracket portion at one end, a pair of last supporting members at the end 25 of the body opposite the offset bracket portion, means for adjusting and maintaining the last supporting members in parallel relation, a heel piece adjustably mounted on the body between the last supporting means and 30 the bracket, and a hinge connected with the bracket for connecting the device to a support.

In testimony whereof I hereunto affix my signature.

FRED R. LONG.
